UNITED STATES PATENT OFFICE.

ALEXANDER S. RAMAGE, OF DETROIT, MICHIGAN, ASSIGNOR TO FRANK F. BEALL,
ALEXANDER S. RAMAGE, AND BENJAMIN BRISCOE, ALL OF DETROIT, MICHIGAN,
TRUSTEES, KNOWN AS CHEMICAL RESEARCH SYNDICATE, LTD.

CONVERSION OF AROMATIC RING COMPOUNDS INTO MOTOR SPIRIT.

No Drawing.

Application filed January 28, 1921. Serial No. 440,744.

To all whom it may concern:

Be it known that I, ALEXANDER S. RAMAGE, a citizen of the United States, residing at Detroit, in the county of Wayne and State 5 of Michigan, have invented certain new and useful Improvements in the Conversion of Aromatic Ring Compounds into Motor Spirit, of which the following is a specification.

10 The object of this invention is to form a low-boiling point motor spirit consisting mainly of compounds of the saturated ring type, such as the cycloparaffins. Under the conditions of use in internal combustion engines the compounds of the olefin type very 15 rapidly polymerize with the formation of resinous compounds which tend to gum the valves; and this same effect has been found to exist even with motor spirits of the paraffin type.

Experience has shown that the least decomposable motor spirit is that containing cyclohexane.

It has been shown by Sabatier that cyclohexane is formed when benzol is hydrogenated by passing the vapors of benzol and hydrogen over a nickel catalyzer at 200° C.

I have discovered that this cyclohexane is more readily formed by exposing the vapors 30 of benzol or like compounds under suitable heat conditions to the action of highly reactive hydrogen, generated by a chemical reaction taking place in presence of the body to be hydrogenated. My preferred reaction 35 for the generation of hydrogen is that of steam upon ferrous oxid at temperatures above 550° C. In the preferred embodiment of my invention the ferrous oxid is continuously regenerated by a reducing reaction involving the ferric oxid and a hydrocarbon 40 gas or vapor other than the aromatic compound to be hydrogenated.

In carrying out my invention in its preferred embodiment I mix with aromatic 45 compounds such as benzene, toluene, xylene, etc., and their homologues, a paraffin or olefin hydrocarbon, and pass the mixture in vapor form, together with superheated steam, over ferrous oxid or a similar sub- 50 oxid capable of decomposing steam, kept at a temperature between 550°-700° C.

The principal reactions which may be in-

volved in the practice of my process are expressed as follows:

1. The oxidation of ferrous oxid to ferric 55 oxid by means of steam at a temperature of from 550° C. to 650° C. with generation of highly reactive or so-called "nascent" hydrogen.

2. The dehydrogenation of saturated hydrocarbon compounds to unsaturated compounds by means of ferric oxid.

3. The splitting up of the unsaturated compounds at high temperatures, of say 650° C., into simpler hydrocarbons such as 65 ethylene.

4. That ethylene or other hydrocarbon gases including methane react with ferric oxid at temperatures of 500° C. to 550° C. yielding ferrous oxid, carbon, and water.

5. That at temperatures of 500° C. to 600° C. carbon reduces ferric oxid to ferrous oxid with formation of carbon monoxid.

6. That at similar temperatures or under, 75 carbon monoxid reduces ferric oxid to ferrous oxid with formation of carbon dioxide.

7. That at 500° C. water is decomposed by ferrous oxid with the formation of ferric oxid and hydrogen.

8. That the hydrogen thus produced readily replaces the methyl group, and carries on the hydrogenation up to the formation of cycloparaffins.

This process is very applicable to the oils distilled from coal, or coke oven tars, as 85 these already contain the mixture of paraffins and aromatic hydrocarbons.

It will be understood that these reactions 90 are occurring simultaneously or in succession. Thus upon the introduction of superheated steam and the heavy hydrocarbon into a retort containing ferrous oxid the ferrous oxid is oxidized to ferric oxid according to the reaction:

Thereupon a reaction which for a specific case chosen for illustration may be expressed as follows, occurs.

This reaction occurs at from 450°-500° C.

At higher temperatures as from 650°-700° C. the compounds represented by the for-

mula $C_{14}H_{30}$ will be decomposed into 7 parts of ethylene C_2H_4 .

The reaction between ethylene and ferric

When 20 molecules of water are added there results:

Therefore from 198 pounds of $C_{14}H_{30}$ and 360 pounds of steam there is produced 60 pounds of nascent hydrogen. This amount is sufficient to completely hydrogenate to 15 a cycloparaffin compound, 10 molecules of benzene or 7 molecules of toluene or 6 molecules of xylene or 5 molecules of mesitylene and cumene. Of course ethylene can be used instead of a paraffin, such as $C_{14}H_{30}$, using 20 the proportions as designated in the equations. The equations representing the hydrogenating effect upon the aromatic compounds may be represented as follows:

In every case some of the C_2H_4 polymerizes to C_4H_8 and C_6H_{12} because the final 30 product contains these compounds to the extent of 10 to 20%.

In the practical operation of the process the mixture of aromatic and paraffin or 35 olefin compounds, such as the vapors from coal tar, is introduced together with a definitely determined quantity of steam into a preferably slightly inclined 4" diameter 40 tube 20' long containing ferrous oxid. The tube is fitted at the entrance end with an orifice valve (a gate valve with a $\frac{1}{2}$ " orifice drilled through the valve) for the delivery of the oil vapors, and also with a gate valve with a $\frac{3}{2}$ " orifice for the superheated steam. 45 With an oil and steam pressure of 10 pounds on the one side, and practically none on the tube side, these valves admit exactly 5 gallons of oil and 8 pounds of steam per hour respectively. As the boiling point of the oil 50 in the vaporizing still rises the amount of steam can be increased by raising the pressure as the temperature rises. The temperature of the tube at the upper or entrance end is kept at about $600^\circ C.$, the temperature 55 gradually increasing to about $700^\circ C.$ at the outlet end.

As a result of the reactions within the

oxid and other simultaneous or successive reactions may be:

5

tube there is produced a mixture of vapors and gases, which, upon condensation, yield a motor spirit entirely free from water and 60 composed principally of cyclohexane (boiling at about $81^\circ C.$) together with light paraffins, some cyclo-olefins and cyclo-paraffins, and also some unchanged aromatics as benzene and its homologues. Such a product 65 is obtained from ordinary coal or coke oven tars which contain mixtures of aromatic compounds, paraffins and olefins.

When the process is carried out under the conditions stated no water as such is found 70 in the condensate. It is important that the steam be always used in the required proportions. Otherwise, if an excess of steam is used, too much FeO is oxidized and the 75 reaction would ultimately come to a cessation. It is preferable therefore not to use more steam than is requisite theoretically to carry out the reaction. After a run of 24 hours, a sample of the oxid drawn from the tube should upon analysis contain neither 80 carbon nor ferric oxid.

It is also essential that the ferrous oxid should not be reduced to metallic iron, since in the presence of iron, carbon is deposited 85 from the oil vapors.

I claim:

1. The continuous process of hydrogenating hydrocarbons consisting essentially of aromatic bodies which comprises passing the hydrocarbons in vapor form, admixed with 90 another non-aromatic hydrocarbon and with steam, in contact with an iron compound substantially maintained in a state of ferrous oxid, at an elevated temperature not below $550^\circ C.$ 95

2. The continuous process of hydrogenating hydrocarbons consisting essentially of aromatic bodies which comprises subjecting the hydrocarbons in vapor form, admixed with another non-aromatic hydrocarbon and 100 with steam to the action of ferrous oxid at an elevated temperature not substantially below $550^\circ C.$, and regulating the proportion of steam to hydrocarbon to maintain the oxid substantially in the ferrous state. 105

In testimony whereof, I affix my signature.

ALEXANDER S. RAMAGE.
